METHOD OF PRODUCING TABLETS OF POWDERY MATERIAL FRAMED IN METAL

Application filed September 12, 1928, Serial No. 305,598, and in Germany September 16, 1927.

To obtain finished pressed articles, for instance buttons of material in powder, tablets are first produced by an intermediate stage which are subsequently pressed in the 5 pressing tool. It happens frequently that such tablets, specially if they have to be coloured and ornamented, are damaged easily, the inserting of the tablets into the pressing tool requiring much time as, for instance 10 at the manufacturing of buttons, pressing tools are used which press 100 or more tablets in one operation.

This invention has for its object to avoid these inconveniences.

15 The improved manufacturing method is as follows:—

The material in powder form is pressed by the pressing piston from below into a hole in a metal plate which has been placed on the 20 pressing chamber, the counter pressing plate with die on the lower surface exerting pressure from above so that a tablet of pressing material is obtained which is securely held on the metal plate. The holding plate with 25 the tablet is then inserted into the pressing tool and the desired shape is given to the tablet by pressing in the usual manner.

The frame plate is preferably made of light metal, for instance an aluminum alloy, 30 and it has a great number of holes so that in one operation a great number of tablets can be pressed to be subsequently treated all at the same time in an accordingly constructed press-tool to obtain the finished articles.

35 A preliminary press and a press-tool for carrying out the improved manufacturing method are diagrammatically illustrated, by way of example, in the accompanying drawings in which

40 Fig. 1 shows in vertical section a press for one single metal framed tablet.

Fig. 2 shows a metal frame with tablet in section.

Fig. 3 shows in side elevation a press tool 45 with metal framed tablet inserted.

Fig. 4 shows the press tool shown in Fig. 3 in the position after the pressing.

The press for producing metal framed tablets as shown in Fig. 1 consists of a press- 50 ing chamber 1 with press piston 2 forming

the movable bottom plate and of an upper press plate 3. The means for operating the press piston and the press plate are not shown as such presses are commonly used.

On the pressing chamber 1 a metal plate 55 4 is placed which has a hole 5 into which the material in powder 6 is pressed by the piston 2 so that the compressed material is securely held in the hole of the metal plate 4 and a metal framed tablet 7 is formed as shown in 60 Fig. 2.

The press tool for producing the desired article, for instance buttons, may be of any convenient construction. It comprises as shown in Figs. 3 and 4 a lower die 8 and an 65 upper die 9 between which the metal framed tablet 7 is placed. When the upper die 9 is lowered upon the lower die 8 the tablet 7 is moulded, the metal frame 4 being at the same time separated from the tablet and pushed 70 over the lower die 8 by the action of a suitable element, for instance a rod 10 fixed in the upper die 9. The tablet might however remain in the metal frame 4 during the pressing. 75

The metal plate 4 may evidently have any desired number of holes, in which case the press tool must comprise a corresponding number of lower and upper dies to simultaneously press all the tablets contained in the 80 metal plate 4.

It is obvious that by the improved method and tools any desired number of tablets may be produced and subsequently moulded simultaneously, this meaning a considerable 85 saving of time so that the output is increased 50%.

The metal plate 4 is preferably made thicker than the tablet to be obtained as shown in Fig. 2 so that the tablets in the 90 holes of plate 4 are well protected against damage at the manipulation and at the storing of the plates.

At hot pressing the pressing operation is accelerated by making the metal tablet frame 95 of light material, for instance an aluminium alloy, as in this case a better heat contact exists between the metal plate and the tablets.

We claim:—

A method of pressing tablets from powder. 100

ous material, consisting in pressing the powderous material into holes in a perforated metal plate which is higher than the tablets pressed, in removing said metal plate with the powderous material still in the holes, and in submitting the material to further treatment whilst in the holes in the perforated plate.

In testimony whereof we affix our signatures.

HERMAN PFLEUMER.
FRANZ KRÜGER.
HEINRICH OEXMANN.
